THERMAL CONTROL DEVICE

Ralph W. Gustafson, Fulton, Ill., assignor to General Electric Company, a corporation of New York

Application May 28, 1952, Serial No. 290,471

10 Claims. (Cl. 200—138)

1

This invention relates to control devices, and more particularly to devices for operating electric switches responsively to temperature changes in a selected location.

The principal object of the invention is to provide a simple, reliable, and easily constructed control device for operating an electric switch or switches in response to the occurrence of predetermined temperatures in the bonnet of a furnace or other similar location.

A more specific object is to provide a combination warm air fan and limit device which normally starts and stops the circulating fan forming part of a warm air furnace and which, in addition, operates to discontinue operation of the furnace in the event that the air temperature becomes excessive for any reason.

A still further object is the provision of a combined warm air fan and limit device as described in the preceding paragraph which, after it has operated to discontinue operation of the furnace, automatically restores itself to its initial condition so that it is ready again to operate normally as a controller for the warm air fan when the operation of the furnace is resumed.

Other objects, advantages and features of my invention will be apparent from the subsequent description of a preferred embodiment thereof, while the scope of the invention is set forth in the appended claims.

In carrying out my invention in one form, I provide a control device having a shaft connected to a helical bimetal member and arranged for rotational movement in either direction responsively to changes in the temperature of the bimetal. A pair of operating members are adjustably mounted on the shaft, and each operating member has an operating arm forming a portion thereof; these arms extend adjacent each other in a direction substantially parallel to the shaft. An electric switch having two positions and snap-action means for maintaining the switch normally in one of these positions is supported in a suitable manner adjacent the two operating arms. A cantilever spring actuating member is provided for the switch, this actuating member being arranged to oppose the said maintaining means with a force such that the switch remains in either of its two positions to which it is moved by movement of the actuating member. A portion of the actuating member extends between the two said operating arms whereby the rotation of the shaft in one direction engages one of the arms with the actuating member and moves the switch to a first of its two positions,

2

and a movement of the shaft in the other direction engages the other of the operating arms with the actuating member and operates the switch to the second of its two positions. A third operating member with an operating arm thereon may be provided on the shaft for operating a second electric switch.

For a clear and more complete understanding of my invention, reference should be had to the accompanying drawing in which

Fig. 1 shows a front elevation view of a combination warm air fan and limit device embodying this invention, with the cover removed and a portion of the device cut away;

15 Fig. 2 is a sectional view along the line 2—2 of Fig. 1;

Fig. 3 is a sectional view along the line 3—3 of Fig. 2;

20 Fig. 4 is an exploded view of a portion of the combined warm air fan and limit device of the preceding figures;

Figs. 5 and 6 are partial views showing different operating positions of the device of the other figures;

25 Fig. 7 is a perspective view of a switch which may be incorporated in the device, and

Fig. 8 is a separate view of the cantilever spring actuating member of Fig. 7.

The control device of the drawing is designated generally by the numeral 10 in Figs. 1 and 2. This control device in its essential elements comprises a metal tubular portion 11 housing a helical bimetal member 12, and a rectangular housing portion 13 which contains a switching mechanism 14 designated generally by the numeral 14.

The tubular portion 11 of the device should be suitable for installation in the warm air bonnet of a furnace or other location, to the temperature of which it is desired that the device respond.

30 Ordinarily, at least all of the portion of member 11 surrounding bimetal 12 is positioned within the heated space, while a portion of the right hand end of tube 11 and the housing 13 project beyond the wall of the heated space. Mounting means (not shown) are ordinarily provided on member 11 to secure the device to such a wall. A section of the right hand portion of tube 11 has been omitted from Figs. 2 and 3 of the drawing, but it should be understood that this portion of tube 11 is made of sufficient length to provide adequate insulation between the portion of tube 11 which is within the warm air chamber and the external housing 13 containing the switching mechanism. Also, it will be readily understood by

35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970

that other insulating means, such as an insulating shield (not shown) around tube 11, for example, may be utilized between housing 13 and the furnace, if necessary, to prevent the switching mechanism within the housing from becoming overheated.

As shown in the drawing, the helical bimetal 12 is mounted upon and supported by a projection 16 of a rotatably adjustable disk 15 which fits within and substantially closes tube 11. Bimetal 12 is secured firmly to projection 16 in a suitable manner such as by spot welding. Disk 15 is connected by a longitudinally disposed member 17 to a second disk 18 which also fits closely within tube 11 in order to close the tube but is rotatable for adjustment purposes. The bimetal 12 and the associated rotatably movable structure 15, 16, 17, 18 are maintained within the tube 11 by an angular portion 19 projecting from disk 18. The projection 19 is adjustably secured to the rear wall 58 of housing 13 by a screw 21 which passes through a slot 20 in projection 19 and engages the threads in a suitable threaded opening in the rear wall 58. The slot 20 in the projection 19 provides for a small rotational adjustment of the bimetal to provide the initial calibration of the control device.

The other or left hand end of the bimetal as seen in Fig. 2 is secured to a shaft 22 in a suitable manner such as by spot welding. The shaft 22 extends longitudinally through helical bimetal 12 and through the suitable openings in disks 15 and 18 into the housing 13. As the temperature of bimetal 12 changes the shaft 22 is caused to rotate in one direction or the other depending upon the direction of temperature change, the disks 15 and 18 providing bearing surfaces for the rotation of shaft 22.

A scale member 23 is rigidly secured to the opposite end of shaft 22 for rotation therewith. As shown, this scale member comprises an assembly of two laminations for ease of manufacture. The inner lamination is of steel and is welded to the shaft 22, while the outer lamination containing suitable indicia is secured to the inner lamination to form a unitary scale member.

As illustrated, the control device includes three operating members 24, 25 and 26 mounted on shaft 22 for rotation with the shaft and scale member 23. These operating members are best seen in Fig. 4 of the drawing, which also shows other elements providing frictional means for holding these operating members for rotation with shaft 22 and scale member 23 and at the same time providing for the adjustment of the operating members with respect to each other and the scale member 23. As shown, these friction means comprise a friction member 27 positioned between operating members 24 and 25, a friction member 28 positioned between operating members 25 and 26, and a spring member 29 which holds operating members 24, 25 and 26 and friction members 27 and 28 adjustably in position against scale member 23. Spring member 29 is curved and has a depressed portion 29a in the center, as seen in Fig. 3, to press against the other members, and may be secured to scale member 23 by a pair of rivets 30 and 31. Friction disk 27 has an arm 32 having an indentation 33 in the end thereof, which indentation embraces rivet 31 and holds friction member 27 fixed with respect to the scale member 23. Friction member 28 has a similar arm 34 with an indentation 35 in the end thereof

which embraces the other rivet 30 to prevent friction disk 28 from moving.

With this arrangement, if the pressure exerted by spring 29 is properly chosen, the operating members 24, 25 and 26 rotate with scale member 23 during operation of the control device, but these operating members may be adjusted with respect to the scale member 23 by restraining the latter member and moving the operating member which it is desired to adjust. To facilitate the adjustment of the operating members, each is provided with a projection which extends through a suitable opening in the scale member 23. These projections are designated respectively 36, 37 and 38 for operating members 24, 25 and 26. Projections 36 and 37 extend through an opening 39 in scale member 23, while projection 38 extends through an opening 40. A projection 41, which is shown as an extension of rivet 30, may be provided on the outer surface of scale member 23 to facilitate holding scale member 23 while one of the operating members is adjusted by moving the outwardly extending portion of one of projections 36, 37 or 38. Fig. 1 shows how indicia may be provided on the outer surface of scale assembly 23 to indicate the settings of the three operating members.

Each of the operating members 24, 25 and 26 operates an electric switch under selected conditions, and for this purpose each of these operating members is provided with an operating arm. These are designated 42, 43 and 44 respectively for operating members 24, 25 and 26. As shown, operating arms 42 and 43 are arranged to operate an enclosed switch 45 while the third operating arm is arranged to operate a second enclosed switch 46. These switches may be secured to the rear wall 58 of housing 13 by means of brackets 47 and 48 respectively. As shown, the brackets 47 and 48 are secured to the rear wall by means of rivets 49 while the switches, in turn, are secured to the brackets by screws 50.

The switches 45 and 46 are of the snap-acting type, each employing an over center or other suitable mechanism to provide snap action, and each having a return spring or other means for causing the respective switch to remain normally in one of two operating positions. One suitable switch mechanism which may be used in these switches is shown in U. S. Patent 2,429,813, granted to George M. Hausler on October 28, 1947, however, many other similar switches providing snap action between two positions and employing a return spring or other restoring means are known and may be used in this control device if desired.

A cantilever spring actuating member 51 made of a suitable resilient material is provided for switch 45, and as shown in the drawing, particularly in Figs. 2, and 5-7, this actuating member is mounted upon an upward extension 52 of switch mounting bracket 47. Actuating member 51 is secured to extension 52 in any suitable manner, such as by spot welding, and arranged to engage an operating button 56 of switch 45. Actuating member 51 is positioned on bracket 47 so that it exerts an operating force on the operating button 56 of switch 45 in a direction opposite to that exerted by the restoring mechanism in the switch. Actuating member 51 should be so chosen and arranged that it exerts a sufficient force on switch 45 that this switch will remain in either of its operating positions. That is, actuating member 51 is so chosen that the force which it exerts is not sufficient completely

to overcome the restoring mechanism of the switch 45, so that the switch will remain in the restored position when moved to such position. At the same time, the actuating member 51 is made strong enough that when the switch 45 is in the unrestored position, it will remain there, that is, the restoring mechanism alone does not have enough force to overcome the actuating member and initiate a restoring operation of the switch.

In one typical device embodying this invention, the switch 45 requires a force of approximately 4 ounces to move it from the restored to the unrestored position, while a force of 2 ounces is required to keep it from resetting. Therefore, actuating member 51 was selected and arranged to maintain a force of approximately 3 ounces over its range of operation.

The spring actuating member 51 is shown separately in Fig. 3 the form which it may assume before it is attached to extension 52 of the switch mounting bracket 47, by spot welding or otherwise. The curvature of the vertically disposed portion of member 51 is in this figure indicative of the fact that when the upper end is secured against a flat vertical surface, such as extension 52, the lower end pushes inwardly on the operating button 56 of switch 45.

The switch 45 is shown in Fig. 5 in the restored position and in Fig. 6 in the unrestored position. When the actuating member 51 is moved to the position shown in Fig. 5, the switch 45 remains in this position until the lower portion of the actuating member is moved to the right by a force external to the switch 45 and actuating member 51. Similarly after the actuating member 51 has been moved to the position shown in Fig. 6, the switch remains in this unrestored position until the lower portion of the actuating member 51 is moved back again to the left.

To provide for the actuating member 51 to move the switch 45 between its two operating positions, there is provided at the lower end of member 51 an integral, transversely disposed, resilient extension portion 53 which as shown herein is approximately hairpin shaped. Extension portion 53 has a downwardly extending offset portion 54 on the lower leg thereof forming a shoulder portion 55 on this leg.

Under normal operating conditions of the control device, the lower leg of resilient extension 53 extends between operating arms 42 and 43, the former being above and the latter below as shown in Figs. 1 and 6. When the bimetal 12 rotates the shaft 22 clockwise a predetermined amount, the arm 42 engages the lower portion of actuating member 51 immediately above the extension portion 53, as shown in Fig. 1, and moves the switch 45 to its unrestored position. If, then, the temperature of bimetal 12 changes in the other direction so that the shaft rotates counterclockwise, the operating arms after a predetermined amount of such clockwise rotation assume the position shown in Fig. 6 in which arm 42 has moved away from actuating member 51 and arm 43 is just about to engage shoulder portion 55 on resilient extension 53. As shaft 22 rotates still further clockwise, operating arm 43, by engaging shoulder portion 55, moves actuating member 51 away from the switch operating button 56 and allows the switch to be restored to its normal quiescent position by its internal restoring mechanism.

If counterclockwise rotation of shaft 22 continues, the operating arm 43 then leaves shoul-

der portion 55 as illustrated in Fig. 5. Ordinarily this does not occur when this control device is used to control a circulating fan for a warm air furnace, as can be readily done by arranging switch 45 to close its contacts in the restored position shown in Fig. 5 and actuate the circulating fan. In such a case, the temperature of the furnace bonnet and consequently the temperature of the bimetal 12 normally will quickly be reduced so that the shaft 22 does not rotate further in a counterclockwise direction. Instead, as the warm air temperature is reduced the bimetal rotates the shaft back clockwise until the operating arm 42 reaches the position shown in Fig. 1 and opens the switch 45 again to discontinue operation of the circulating fan.

If, however, the temperature of the furnace bonnet or other space in which bimetal 12 is located increases abnormally, for any reason, the shaft 22 is rotated counterclockwise to the position shown in Fig. 5, the operating arm 43 being released from the shoulder portion 55 of the switch actuating member 53 as this rotation takes place due to the resiliency of this switch actuating member and the proper proportioning and arrangement of shoulder 55 and arm 43. At the position shown in Fig. 5 the third operating arm 44 engages the operating button 57 of the second switch 46 and operates this switch to discontinue the operation of the furnace or other apparatus to prevent damage or the creation of a potentially dangerous condition; the mechanism is shown in Fig. 5 just after operating arm 44 has completed depressing the button 57 to operate switch 46.

When the abnormal condition causing an excessive temperature has been corrected, the bimetal cools and rotates shaft 22 clockwise again. When this occurs the operating arm 43 engages offset portion 54 of the switch actuating member and raises extension 53 on the switch actuating member sufficiently that the arm 43 passes under extension 53 and the moving portion of the device returns to the position shown in Fig. 1. This clockwise movement opens switch 46 as soon as it starts movement, and ultimately opens switch 45 again when the position illustrated in Fig. 1 is reached. Thereafter, the control device will again operate normally to close and open switch 45 providing the condition which caused the excessive temperature has been corrected so that the furnace or apparatus being controlled by this device operates normally.

When this device is used to control a circulating fan by operating switch 45 to close and open an actuating circuit for such a fan, it is generally desirable that a certain minimum differential be maintained between the temperature at which the fan comes on and the temperature at which it goes off again. Such a minimum differential is readily provided in the present device merely by making the portion 12 of operating member 24 of sufficient width that it keeps operating arm 43 on operating member 25 at a desired minimum distance from operating arm 42 on member 24. It is readily apparent from Fig. 4 of the drawing that the width of portion 12 determines the minimum spacing between arms 42 and 43, and this spacing together with the location of shoulder 55 with respect to the vertical portion of actuating member 51 determines the differential between on and off temperatures for the circulating fan.

In addition to the preceding, it is generally desirable also that the device be arranged so that switch 46 cannot be operated until switch 45

has operated; thus, when the device is used as a combined warm air fan and limit controller, the device cannot be set to operate the limit switch 46 before switch 45 has turned on the fan. This is accomplished by providing at the proper location on operating member 25 an ear portion 25a which engages arm 44 on member 26 in case it should be attempted to adjust members 25 and 26 in a manner which would provide other than a proper sequence of operation for the two switches.

The housing 13 as shown in the drawing includes a rear wall 58, a top wall 59, a bottom wall 60, and two partial side walls 61. The housing is closed by a cover member 62 which is substantially U-shaped, having an elongated front portion 63 and a pair of elongated side portions 64. The cover may be secured to the remainder of the housing by a pair of screws 65, only one of which is shown, which engage suitable threaded apertures 66 in projections 67 extending inwardly from the top and bottom walls 59 and 60. Within the housing there may be provided a flat member 68 of insulating material which is secured to inwardly turned projections 69 on the partial side walls 61 of the housing by means of screws 70 which engage suitable threaded apertures 71 in projections 69. As shown, insulating member 68 has an opening in which scale member 23 is located, with the outer surface of the scale member approximately flush with the outer surface of insulating member 68. If desired, terminals 72 may be provided at the bottom of insulating member 68. As will be readily understood, these terminals ordinarily are connected to the switches 45 and 46, although the conductors for this purpose have been omitted from the accompanying drawing in order to simplify it. The control device 10 is connected to the apparatus which it is to control by external conductors brought into the enclosure 13 and connected to terminals 72.

It will be apparent from the foregoing that my invention provides a simple and easily constructed control device which may be used, for example, as a warm air fan and limit device for a furnace. Moreover, the device automatically restores itself to its initial normal operating condition after an excessive temperature so that it is ready again for normal operation as soon as the cause of the excessive temperature has been removed.

While I have illustrated my control device as embodying a bimetal element making it responsive to temperature changes, it will be readily understood that other physical condition responsive devices may be substituted, if desired. Furthermore, this invention is not limited to use with a rotating shaft but is adaptable, also, for use with operating members having rectilinear or other motions.

Other modifications likewise will occur to those skilled in the art and, therefore, it should be understood that I intend to cover by the appended claims all such modifications which fall within the true spirit and scope of my invention.

What I claim as new and desire to secure by Letters Patent of the United States is:

1. A control device comprising, a shaft member arranged for rotational movement in either direction, a pair of operating members adjustably mounted on said shaft, each operating member having an operating arm and the two said arms extending adjacent each other, a switch having two positions and snap action means

5 maintaining said switch normally in one of said positions, and a cantilever spring actuating member for said switch arranged to oppose the said maintaining means with a force such that said switch remains in either of the said two positions to which it is moved by movement of the said actuating member, a portion of the said actuating member being located between the said two arms whereby the rotation of the said shaft in one direction engages one of said arms with the said actuating member and operates the said switch to a first of the said two positions and the rotation of the shaft in the other direction engages the other arm with the actuating member and operates the switch to the second of the two positions.

2. A control device comprising, a first member arranged for movement in either of two opposite directions, a pair of operating members adjustably mounted on said first member, each operating member having an operating arm and the two said arms extending adjacent each other, a switch having two positions and means maintaining said switch normally in one of said positions, and a spring actuating member for said switch arranged to oppose the said maintaining means with a force such that said switch remains in either of the said two positions to which it is moved by movement of the said actuating member, a portion of the said actuating member being located between the said two arms whereby the movement of the said first member in one direction engages one of the said arms with the actuating member and operates the said switch to a first of said two positions and the movement of the first member in the opposite direction engages the other arm with the actuating member and operates the switch to the second of the two positions.

3. A control device comprising, physical condition responsive means, a first member connected to said condition responsive means and arranged for movement in either of two opposite directions responsive to changes in the physical condition, a pair of operating members adjustably mounted on said first member, each operating member having an operating arm and the two said arms extending adjacent each other, a switch having two positions and restoring means normally maintaining said switch in one of the said positions, an actuating member for said switch for moving it to either of the said two positions, said actuating member being arranged to oppose the said restoring means with a force such that said switch remains in either of the two positions to which it is moved, a portion of said actuating member being located between the said two arms whereby the movement of the said first member in one direction engages one of the said arms with the actuating member and operates the said switch to a first of the said two positions and the movement of the first member in the opposite direction engages the other arm with the actuating member and operates the switch to the second of the two positions.

4. A control device comprising, physical condition responsive means, a shaft member arranged for rotational movement in either direction responsively to changes in said condition responsive means, a pair of operating members adjustably mounted on said shaft, each operating member having an operating arm and the two said arms extending adjacent each other and substantially parallel to said shaft, a switch

having two positions and means for maintaining said switch normally in one of said positions, a cantilever spring actuating member for said switch for moving it to either of the said two positions, said actuating member being arranged to oppose the said maintaining means with a force such that said switch remains in either of the said two positions to which it is moved, a resilient extension portion on said actuating member extending transversely of the said shaft and between the said first and second arms, and a shoulder portion of said resilient extension portion for engaging one of said arms, whereby when said shaft rotates in one direction responsively to a change in said physical condition in a certain direction said one arm engages said shoulder portion and actuates said switch to a first of its two positions, and when said shaft rotates in the opposite direction responsively to a change in the physical condition in the other direction said second arm engages said actuating member and moves said switch to the second of its two positions.

5. A thermal control device comprising, a helical bimetal member, a shaft connected to said bimetal member for rotational movement in either direction responsively to changes in the temperature of the said bimetal, a pair of operating members adjustably mounted on said shaft each provided with an operating arm, the two said operating arms extending adjacent each other and substantially parallel with said shaft with one arm more remote from the shaft than the other, a switch having two positions and snap action means maintaining said switch normally in one of said positions, a cantilever spring actuating member for said switch arranged to oppose the said maintaining means with a force such that said switch remains in either of the said two positions to which it is moved by movement of the said actuating member, a resilient extension portion on said actuating member extending transversely of the said shaft and between the said first and second arms, and a shoulder portion on said resilient extension portion for engaging one of said arms when said bimetal rotates said shaft in one direction responsively to a change in the temperature of the bimetal in a certain direction whereby said switch is actuated to the first of its two positions, the other arm engaging said actuating member upon rotation of said shaft in the opposite direction responsively to a change in the temperature of the bimetal in the opposite direction and moving said switch to the second of its two positions.

6. A thermal control device comprising, a helical bimetal member, a shaft connected to said bimetal member for rotational movement in either direction responsively to changes in the temperature of the said bimetal, an indicating scale member secured to one end of said shaft and arranged for rotation therewith, a pair of operating members arranged on said shaft adjacent the said scale member, means secured to said scale member for yieldingly urging said operating member toward the scale member so as to be rotatable therewith, friction means in contact with the said operating members providing for the rotational adjustment of the operating members with respect to each other and the scale member, a pair of operating arms forming portions respectively of the said operating members and extending away from said scale member in substantially parallel relation with the said shaft, a first one of said operating arms being adjacent to the second

arm but at a greater distance from the said shaft than the said second arm, an electric switch having two positions and snap action means for maintaining said switch normally in one of the said two positions, a cantilever spring actuating member for said switch arranged to oppose the said maintaining means for the said switch with a force such that said switch remains in either of the said two positions to which it is moved by the movement of the said actuating member, a resilient substantially right-angle extension portion on said actuating member extending transversely of the said shaft and between the said first and second arms, and an offset portion on said resilient extension portion forming a shoulder which engages said second arm when said bimetal rotates said shaft in one direction responsively to a change in the temperature of the bimetal in a predetermined direction whereby said switch is actuated to the first of its two positions, said first arm engaging said actuating member upon rotation of said shaft in the opposite direction responsively to a change in the temperature of the bimetal in the opposite direction and moving said switch to the second of its two positions.

7. A control device comprising, a first member arranged for movement in either of two opposite directions, a pair of operating members adjustably mounted on said first member, each operating member having an operating arm and the two said arms extending adjacent each other, a switch having two positions and means maintaining said switch normally in one of said positions, a spring actuating member for said switch arranged to oppose the said maintaining means with a force such that said switch remains in either of the said two positions to which it is moved by movement of the said actuating member, a portion of the said actuating member being located between the said two arms whereby the movement of the said first member in one direction engages one of the said arms with the actuating member and operates the said switch to a first of said two positions and the movement of the first member in the opposite direction engages the other arm with the actuating member and operates the switch to the second of the two positions, a third operating member provided with an operating arm and adjustably mounted on said first member, and a second electric switch arranged to be operated by the arm of said third operating member upon movement of said first member in said one direction a predetermined amount beyond the amount necessary to operate said first switch to its said first position.

8. A control device comprising, a shaft member arranged for rotational movement in either direction, a pair of operating members adjustably mounted on said shaft, each operating member having an operating arm and the two said arms extending adjacent each other, a switch having two positions and snap action means maintaining said switch normally in one of said positions, a cantilever spring actuating member for said switch arranged to oppose the said maintaining means with a force such that said switch remains in either of the said two positions to which it is moved by movement of the said actuating member, a portion of the said actuating member being located between the said two arms whereby the rotation of the said shaft in one direction engages one of said arms with the said actuating member and operates the said switch to a first of the said two positions and the rotation of the shaft in the other direction engages

the other arm with the actuating member and operates the switch to the second of the two positions, a third operating member having an operating arm and mounted adjustably on said shaft, and a second electric switch arranged to be operated by the arm of said third operating member upon movement of said shaft in said one direction beyond the point at which said first switch is operated to its said first position.

9. A thermal control device comprising, a helical bimetal member, a shaft member arranged for rotational movement in either direction responsively to changes in the temperature of said bimetal, a pair of operating members adjustably mounted on said shaft and each provided with an operating arm, the two said operating arms extending adjacent each other and substantially parallel with said shaft with one arm more remote from the shaft than the other, a switch having two positions and a restoring means normally maintaining said switch in one of said positions, a cantilever spring actuating member for said switch arranged to oppose the said restoring means with a force such that said switch remains in either of the said two positions to which it is moved by movement of the said actuating member, a resilient extension portion on said actuating member extending transversely of the said shaft and between the said two operating arms, a shoulder portion on said resilient extension portion for engaging the less remote of said arms when said shaft is rotated in one direction thereby to actuate said switch to its restored position, the second arm engaging said actuating member upon rotation of said shaft in the opposite direction and moving said switch to its non-restored position, a third operating member having a third operating arm and adjustably mounted on said shaft, and a second electric switch arranged to be operated by the said third arm upon rotation of said shaft in said one direction a predetermined amount beyond the amount necessary to operate the said first switch to its restored position.

10. A combination warm air fan and limit device comprising, a helical bimetal member, a shaft connected to said bimetal member for rotational movement in either direction responsively to changes in the temperature of the said bimetal, an indicating scale member secured to one end of said shaft and arranged for rotation therewith, three operating members arranged on said shaft adjacent the said scale member, means secured to the said scale member for yieldingly urging all of the said operating members toward the scale member so as to be rotatable therewith, friction means in contact with the said operating

members providing for the rotational adjustment of the operating members with respect to each other and the scale member, three operating arms forming portions respectively of the said three operating members and extending away from said scale member in substantially parallel relation with the said shaft, a first one of said operating arms being adjacent to a second one of the said arms but at a greater distance from said shaft than the said second arm, a first electric switch having two positions and snap action means maintaining said switch normally in one of said two positions, a cantilever spring actuating member for said first switch arranged to oppose the said maintaining means for said first switch with a force such that said first switch remains in either of the said two positions to which it is moved by the movement of the said actuating member, a resilient substantially right angle extension portion on said actuating member extending transversely of the said shaft and between the said first and second arms, an offset portion on said resilient extension portion forming a shoulder which engages said second arm when said bimetal rotates said shaft in one direction responsively to a change in temperature of the bimetal in a certain direction and thereby actuates said first switch to a first of its two positions, said first arm engaging said actuating member upon rotation of said shaft in the opposite direction responsively to a change in the temperature of the bimetal in the opposite direction and moving said switch to the second of its two positions, said resilient extension portion being arranged so that said second arm is released by the shoulder thereon if the said bimetal rotates said shaft more than a selected amount in said one direction, and a second electric switch arranged to be operated by said third arm upon the rotation of said shaft in said one direction a predetermined amount after the release of said second arm by said shoulder.

RALPH W. GUSTAFSON.
